UNITED STATES PATENT OFFICE.

ERNEST O. SEITZ, OF DETROIT, MICHIGAN, ASSIGNOR TO C. M. HALL LAMP CO., OF DETROIT, MICHIGAN, A CORPORATION OF MICHIGAN.

DESIGN FOR A LAMP DOOR.

Application filed March 26, 1923. Serial No. 5,590. Term of patent 14 years.

To all whom it may concern:

Be it known that I, ERNEST O. SEITZ, a citizen of the United States of America, residing at Detroit, in the county of Wayne and State of Michigan, have invented a certain new, original, and ornamental Design for a Lamp Door, of which the following is a specification, reference being had therein to the accompanying drawings, forming part thereof, in which—

I claim:

The ornamental design for a lamp door, substantially as shown.

ERNEST O. SEITZ.
